Primary Examiner—Raphael Barkai(74) *Attorney, Agent, or Firm*—McCarter & English, LLP(57) **CLAIM**

I claim, the ornamental design for an automatic contact lens applicator, as shown and described.

DESCRIPTION

FIG. 1 is a side perspective view of an automatic contact lens applicator showing my new design;

FIG. 2 is a side elevational view of the applicator of FIG. 1; FIG. 3 is a front elevational view of the applicator of FIG. 1;

FIG. 4 is a rear elevational view of the applicator of FIG. 1; FIG. 5 is a bottom plan view of the applicator of FIG. 1; and, FIG. 6 is a top plan view of the applicator of FIG. 1.

The broken lines shown in the drawing figures are for illustrative purposes only and form no part of the claimed design.
